(57) **ABSTRACT**

An image forming apparatus to which a cartridge including a cartridge substrate is attachable includes a main body electrical substrate, a main body ground terminal connected to the main body electrical substrate and configured to take a ground voltage, a first main body terminal connected to the main body electrical substrate and configured to transmit one of a power supply voltage, a data signal that indicates information, and a synchronization signal, a second main body terminal connected to the main body electrical substrate and configured to transmit remaining two of the power supply voltage, the data signal, and the synchronization signal.

The cartridge substrate includes a cartridge ground terminal connected to the main body ground terminal, a first cartridge terminal connected to the first main body terminal, and a second cartridge terminal connected to the second main body terminal.

REFERENCE TO RELATED APPLICATIONS

This is a continuation application of International Application No. PCT/JP2020/025220 filed on Jun. 26, 2020 which claims priority from Japanese Patent Application No. 2020-033574 filed on Feb. 28, 2020. The entire contents of the earlier applications are incorporated herein by reference.

BACKGROUND ART

In the related art, an electrophotographic image forming apparatus such as a laser printer or an LED printer has been known. The image forming apparatus includes a drum cartridge and a toner cartridge. The drum cartridge includes a photosensitive drum. The toner cartridge includes a developing roller. The toner cartridge is attachable to and detachable from the drum cartridge. When the toner cartridge is attached to the drum cartridge, the developing roller of the toner cartridge is in contact with the photosensitive drum of the drum cartridge.

In the related art, there has been known that in the image forming apparatus in the related art, a memory is mounted in one or both of the toner cartridge and the drum cartridge.

DESCRIPTION

In such an image forming apparatus, it is necessary to perform (1) taking of a ground voltage, (2) transmitting of a power supply voltage, (3) transmitting of a data signal, and (4) transmitting of a synchronization signal between a substrate included in a main body of the image forming apparatus and the memory included in the cartridge. Therefore, in order to realize (1) to (4), four parallel terminals are usually required. However, in order to reduce sizes of an image forming apparatus and a cartridge, the number of terminals is required to be reduced.

An object of the present disclosure is to provide a technique capable of reducing the number of terminals that electrically connect a substrate included in a main body of an image forming apparatus with a memory included in a cartridge.

A first aspect of disclosure is an image forming apparatus to which a cartridge that includes a cartridge substrate including a memory is attachable, the image forming apparatus including a main body electrical substrate, a main body ground terminal electrically connected to the main body electrical substrate, the main body ground terminal being configured to take a ground voltage, a first main body terminal electrically connected to the main body electrical substrate, the first main body terminal being configured to transmit one of a power supply voltage higher than the ground voltage, a data signal that indicates information written into the memory or read out from the memory, and a synchronization signal taking a timing of the data signal, a second main body terminal electrically connected to the main body electrical substrate, the second main body terminal being configured to transmit remaining two of the power supply voltage, the data signal, and the synchronization signal, and a main body frame to which the cartridge is attachable. The cartridge substrate includes a cartridge ground terminal electrically connected to the main body ground terminal in a state where the cartridge is attached to

the main body frame a first cartridge terminal electrically connected to the first main body terminal in the state, and a second cartridge terminal electrically connected to the second main body terminal in the state.

5 A second aspect of disclosure is the image forming apparatus according to the first aspect of disclosure. The memory includes a timer configured to generate a clock signal. The synchronization signal is a reset signal for resetting the timer.

10 A third aspect of disclosure is the image forming apparatus according to the first aspect of disclosure. The synchronization signal is a clock signal.

15 A fourth aspect of disclosure is the image forming apparatus according to the first aspect of disclosure. The first main body terminal is configured to transmit the power supply voltage. The second main body terminal is configured to transmit the data signal and the synchronization signal.

20 A fifth aspect of disclosure is the image forming apparatus according to the fourth aspect of disclosure. The cartridge substrate further includes a cartridge pull-up resistor including one end connected to the first cartridge terminal and the other end connected to the second cartridge terminal.

25 A sixth aspect of disclosure is the image forming apparatus according to the fourth aspect of disclosure. The main body electrical substrate includes a main body pull-up resistor including one end connected to the first main body terminal and the other end connected to the second main body terminal.

30 A seventh aspect of disclosure is the image forming apparatus according to the fourth aspect of disclosure. The main body electrical substrate includes a switch configured to switch between supply and stop of the power supply voltage to the first main body terminal and a processor configured to control the switch.

35 An eighth aspect of disclosure is the image forming apparatus according to the seventh aspect of disclosure. The main body electrical substrate further includes a main body pull-down resistor that includes one end connected to the first main body terminal and the other end connected to the main body ground terminal.

40 A ninth aspect of disclosure is the image forming apparatus according to the fourth aspect of disclosure. The memory is configured to be driven by obtaining a voltage from a signal supplied from the second cartridge terminal.

45 A tenth aspect of disclosure is the image forming apparatus according to the first aspect of disclosure. The first main body terminal is configured to transmit a clock signal being the synchronization signal. The second main body terminal is configured to transmit the data signal.

50 An eleventh aspect of disclosure is the image forming apparatus according to the tenth aspect of disclosure. The memory is configured to be driven by obtaining a voltage from a signal supplied from the first cartridge terminal or the second cartridge terminal.

55 A twelfth aspect of disclosure is the image forming apparatus according to the first aspect of disclosure. The cartridge includes a toner cartridge including a toner substrate being the cartridge substrate and a drum cartridge including a photosensitive drum, the drum cartridge including a drum substrate being the cartridge substrate. The drum substrate is electrically connected to the main body electrical substrate through the toner substrate.

60 A thirteenth aspect of disclosure is the image forming apparatus according to the twelfth aspect of disclosure. The toner cartridge includes a developing roller.

A fourteenth aspect of disclosure is the image forming apparatus according to the first aspect of disclosure. The main body electrical substrate includes a main substrate including a processor and a relay substrate configured to relay connection between the main substrate and the cartridge substrate.

A fifteenth aspect of disclosure is the image forming apparatus according to the first aspect of disclosure. The memory is configured to store the information used by the image forming apparatus.

A sixteenth aspect of disclosure is the image forming apparatus according to the fifteenth aspect of disclosure. The information includes at least one of identification information and lifetime information of the cartridge. The main body electrical substrate is configured to read out the information as the data signal from the memory, and to store the information in a main body memory mounted on the main body electrical substrate.

According to first to sixteenth aspects of the disclosure, it is possible to realize, by three parallel terminals, (1) taking of the ground voltage, (2) transmitting of the power supply voltage, (3) transmitting of the data signal, and (4) transmitting of the synchronization signal between the main body electrical substrate and the cartridge substrate. As a result, the number of terminals can be reduced as compared with a case where (1) to (4) are realized by four parallel terminals.

According to a fifth aspect of the disclosure, in the cartridge substrate, the data signal and the synchronization signal are less likely to be influenced by noise. As a result, even when a wiring between the main body electrical substrate and the cartridge substrate is long, the data signal and the synchronization signal can be stably transmitted.

According to a sixth aspect of the disclosure, in the main body electrical substrate, the data signal and the synchronization signal are less likely to be influenced by noise. As a result, even when a wiring between the main body electrical substrate and the cartridge substrate is long, the data signal and the synchronization signal can be stably transmitted.

According to a seventh aspect of the disclosure, power consumption can be reduced by turning off a switch when the power supply voltage is unnecessary.

According to an eighth aspect of the disclosure, static electricity entering a first main body terminal can be released to ground through a main body pull-down resistor.

FIG. 1 is a conceptual diagram of an image forming apparatus.

FIG. 2 is a block diagram showing electrical connection between a main body electrical substrate and each of four toner substrates.

FIG. 3 is a conceptual diagram of an image forming apparatus.

FIG. 4 is a block diagram showing electrical connection among the main body electrical substrate, the four toner substrates, and four drum substrates.

FIG. 5 is a block diagram showing electrical connection among the main body electrical substrate, the four toner substrates, and the four drum substrates.

FIG. 6 is a block diagram showing electrical connection among the main body electrical substrate, the four toner substrates, and the four drum substrates.

FIG. 7 is a block diagram showing electrical connection among the main body electrical substrate, the four toner substrates, and the four drum substrates.

FIG. 8 is a block diagram showing electrical connection among the main body electrical substrate, the four toner substrates, and the four drum substrates.

FIG. 9 is a block diagram showing electrical connection between the main body electrical substrate and each of the four toner substrates.

FIG. 10 is a block diagram showing electrical connection between the main body electrical substrate and each of the four toner substrates.

Hereinafter, embodiments of the present disclosure will be described with reference to drawings.

10

1. First Embodiment

<1-1. With regard to Configuration of Image Forming Apparatus>

FIG. 1 is a conceptual diagram of an image forming apparatus 1 according to a first embodiment. The image forming apparatus 1 is an electrophotographic printer. Examples of the image forming apparatus 1 include a laser printer or an LED printer. As shown in FIG. 1, the image forming apparatus 1 includes a main body frame 10, a main body electrical substrate 20, four drum cartridges 30a, 30b, 30c, and 30d, and four toner cartridges 40a, 40b, 40c, and 40d.

The main body electrical substrate 20 includes a main substrate 50 and a relay substrate 60. The main substrate 50 is a plate-shaped electric circuit board. The main substrate 50 includes a processor 51. The processor 51 may be a CPU or an MPU, or may be an application specific integrated circuit (ASIC). The processor 51 operates in accordance with a program, so that the main substrate 50 executes various processes in the image forming apparatus 1. Specifically, the main substrate 50 writes information into each of toner memories 71a, 71b, 71c, and 71d to be described later and reads out the information from each of the toner memories 71a, 71b, 71c, and 71d. Further, the main substrate 50 causes the image forming apparatus 1 to execute a printing process based on the information read out from each of the toner memories 71a, 71b, 71c, and 71d.

The relay substrate 60 is a plate-shaped electric circuit board. The relay substrate 60 relays electrical connection between the main substrate 50 and each of toner substrates 70a, 70b, 70c, and 70d to be described later. The main substrate 50 and the relay substrate 60 are electrically connected to each other.

The drum cartridges 30a, 30b, 30c, and 30d, and the toner cartridges 40a, 40b, 40c, and 40d are each an example of a "cartridge".

The toner cartridge 40a can be attached to the drum cartridge 30a. The drum cartridge 30a to which the toner cartridge 40a is attached can be attached to the main body frame 10. The toner cartridge 40b can be attached to the drum cartridge 30b. The drum cartridge 30b to which the toner cartridge 40b is attached can be attached to the main body frame 10. The toner cartridge 40c can be attached to the drum cartridge 30c. The drum cartridge 30c to which the toner cartridge 40c is attached can be attached to the main body frame 10. The toner cartridge 40d can be attached to the drum cartridge 30d. The drum cartridge 30d to which the toner cartridge 40d is attached can be attached to the main body frame 10.

The four toner cartridges 40a, 40b, 40c, and 40d store therein toner (developers) of different colors (for example, colors of cyan, magenta, yellow, and black), respectively. The image forming apparatus 1 forms an image on a surface of a print sheet by the toner supplied from the four toner cartridges 40a, 40b, 40c, and 40d.

The drum cartridge 30a includes a photosensitive drum 31a. The drum cartridge 30b includes a photosensitive drum

31b. The drum cartridge 30c includes a photosensitive drum 31c. The drum cartridge 30d includes a photosensitive drum 31d. The photosensitive drums 31a, 31b, 31c, and 31d are components that transfer, to the print sheet, the toner supplied from the toner cartridges 40a, 40b, 40c, and 40d. The photosensitive drums 31a, 31b, 31c, and 31d each include a cylindrical outer circumferential surface. The outer circumferential surfaces of the photosensitive drums 31a, 31b, 31c, and 31d are each covered with a photosensitive material. Further, the photosensitive drums 31a, 31b, 31c, 31d are each rotatable about a central axis.

The toner cartridge 40a includes a developing roller 41a and the toner substrate 70a. The toner cartridge 40b includes a developing roller 41b and the toner substrate 70b. The toner cartridge 40c includes a developing roller 41c and the toner substrate 70c. The toner cartridge 40d includes a developing roller 41d and the toner substrate 70d.

The developing rollers 41a, 41b, 41c, and 41d are rotatable rollers. In a state where the toner cartridge 40a is attached to the drum cartridge 30a, an outer circumferential surface of the developing roller 41a is in contact with the outer circumferential surface of the photosensitive drum 31a. In a state where the toner cartridge 40b is attached to the drum cartridge 30b, an outer circumferential surface of the developing roller 41b is in contact with the outer circumferential surface of the photosensitive drum 31b. In a state where the toner cartridge 40c is attached to the drum cartridge 30c, an outer circumferential surface of the developing roller 41c is in contact with the outer circumferential surface of the photosensitive drum 31c. In a state where the toner cartridge 40d is attached to the drum cartridge 30d, an outer circumferential surface of the developing roller 41d is in contact with the outer circumferential surface of the photosensitive drum 31d.

The toner stored in the toner cartridge 40a is supplied to the outer circumferential surface of the photosensitive drum 31a through the developing roller 41a. The toner stored in the toner cartridge 40b is supplied to the outer circumferential surface of the photosensitive drum 31b through the developing roller 41b. The toner stored in the toner cartridge 40c is supplied to the outer circumferential surface of the photosensitive drum 31c through the developing roller 41c. The toner stored in the toner cartridge 40d is supplied to the outer circumferential surface of the photosensitive drum 31d through the developing roller 41d.

The toner substrates 70a, 70b, 70c, and 70d are each an example of a "cartridge substrate". The toner substrate 70a is located at an outer surface of the toner cartridge 40a. The toner substrate 70b is located at an outer surface of the toner cartridge 40b. The toner substrate 70c is located at an outer surface of the toner cartridge 40c. The toner substrate 70d is located at an outer surface of the toner cartridge 40d.

When the drum cartridge 30a to which the toner cartridge 40a is attached is attached to the main body frame 10, the toner substrate 70a is electrically connected to the main body electrical substrate 20. When the drum cartridge 30b to which the toner cartridge 40b is attached is attached to the main body frame 10, the toner substrate 70b is electrically connected to the main body electrical substrate 20. When the drum cartridge 30c to which the toner cartridge 40c is attached is attached to the main body frame 10, the toner substrate 70c is electrically connected to the main body electrical substrate 20. When the drum cartridge 30d to which the toner cartridge 40d is attached is attached to the main body frame 10, the toner substrate 70d is electrically connected to the main body electrical substrate 20.

<1-2. Configuration of Main Body Electrical Substrate>

FIG. 2 is a block diagram showing electrical connection between the main body electrical substrate 20 and each of the four toner substrates 70a, 70b, 70c, and 70d. As described above, the main body electrical substrate 20 includes the main substrate 50 and the relay substrate 60.

As shown in FIG. 2, the main substrate 50 includes the above processor 51, a power supply unit 52, a ground portion 53, a switch 54, a first main terminal 55, four second main terminals 56a, 56b, 56c, and 56d, a main ground terminal 57, four main body pull-up resistors 58a, 58b, 58c, and 58d, and a main body pull-down resistor 59.

The power supply unit 52 is connected to an external power supply. Therefore, a potential of the power supply unit 52 is a constant power supply voltage. The ground portion 53 is connected to an external ground line. Therefore, a potential of the ground portion 53 is a constant ground voltage. The power supply voltage is higher than the ground voltage.

As the switch 54, for example, a switch element such as a transistor is used. The processor 51 can perform switching from turning off to turning on of the switch 54 and switching from turning on to turning off of the switch 54 by transmitting a switching signal to the switch 54.

The first main terminal 55 is electrically connected to the power supply unit 52 through the switch 54. Therefore, when the switch 54 is turned on, the power supply voltage is supplied from the power supply unit 52 to the first main terminal 55. The four second main terminals 56a, 56b, 56c, and 56d are each electrically connected to the processor 51. The main ground terminal 57 is electrically connected to the ground portion 53. Therefore, a potential of the main ground terminal 57 is the ground voltage.

The main body pull-up resistors 58a, 58b, 58c, and 58d are electrical resistors. One end of each of the main body pull-up resistors 58a, 58b, 58c, and 58d is electrically connected to the first main terminal 55. The other end of the main body pull-up resistor 58a is electrically connected to the second main terminal 56a. The other end of the main body pull-up resistor 58b is electrically connected to the second main terminal 56b. The other end of the main body pull-up resistor 58c is electrically connected to the second main terminal 56c. The other end of the main body pull-up resistor 58d is electrically connected to the second main terminal 56d.

The main body pull-down resistor 59 is an electrical resistor. One end of the main body pull-down resistor 59 is electrically connected to the first main terminal 55. The other end of the main body pull-down resistor 59 is electrically connected to the main ground terminal 57 and the ground portion 53.

The relay substrate 60 includes a first relay terminal 61, four second relay terminals 62a, 62b, 62c, and 62d, a relay ground terminal 63, four first main body terminals 64a, 64b, 64c, and 64d, four second main body terminals 65a, 65b, 65c, and 65d, and four main body ground terminals 66a, 66b, 66c, and 66d.

The first relay terminal 61 is electrically connected to the above first main terminal 55. Further, the four first main body terminals 64a, 64b, 64c, and 64d are electrically connected to the first relay terminal 61. Therefore, when the above switch 54 is turned on, the power supply voltage is supplied from the power supply unit 52, through the first main terminal 55 and the first relay terminal 61, to the first main body terminals 64a, 64b, 64c, and 64d. That is, the first main body terminals 64a, 64b, 64c, and 64d are each a terminal that transmits the power supply voltage.

The second relay terminal **62a** is electrically connected to the above second main terminal **56a**. The second relay terminal **62b** is electrically connected to the above second main terminal **56b**. The second relay terminal **62c** is electrically connected to the above second main terminal **56c**. The second relay terminal **62d** is electrically connected to the above second main terminal **56d**.

The second main body terminal **65a** is electrically connected to the second relay terminal **62a**. The second main body terminal **65b** is electrically connected to the second relay terminal **62b**. The second main body terminal **65c** is electrically connected to the second relay terminal **62c**. The second main body terminal **65d** is electrically connected to the second relay terminal **62d**.

The processor **51** can transmit a data signal and a synchronization signal to the second main body terminal **65a** through the second main terminal **56a** and the second relay terminal **62a**. The processor **51** can transmit a data signal and a synchronization signal to the second main body terminal **65b** through the second main terminal **56b** and the second relay terminal **62b**. The processor **51** can transmit a data signal and a synchronization signal to the second main body terminal **65c** through the second main terminal **56c** and the second relay terminal **62c**. The processor **51** can transmit a data signal and a synchronization signal to the second main body terminal **65d** through the second main terminal **56d** and the second relay terminal **62d**.

That is, the second main body terminals **65a**, **65b**, **65c**, and **65d** are each a terminal that transmits the data signal and the synchronization signal. The data signal is a signal that indicates the information written into a respective one of the toner memories **71a**, **71b**, **71c**, and **71d** to be described later or read out from the respective one of the toner memories **71a**, **71b**, **71c**, and **71d**. The synchronization signal is a signal taking a timing of the data signal.

The relay ground terminal **63** is electrically connected to the above main ground terminal **57**. The four main body ground terminals **66a**, **66b**, **66c**, and **66d** are electrically connected to the relay ground terminal **63**. Therefore, potentials of the four main body ground terminals **66a**, **66b**, **66c**, and **66d** are each the ground voltage. That is, the four main body ground terminals **66a**, **66b**, **66c**, and **66d** are each a terminal that takes the ground voltage.

<1-3. Configurations of Toner Substrates>

The toner substrate **70a** includes the toner memory **71a**. The toner memory **71a** is a storage medium that stores information related to the toner cartridge **40a**. The toner substrate **70b** includes the toner memory **71b**. The toner memory **71b** is a storage medium that stores information related to the toner cartridge **40b**. The toner substrate **70c** includes the toner memory **71c**. The toner memory **71c** is a storage medium that stores information related to the toner cartridge **40c**. The toner substrate **70d** includes the toner memory **71d**. The toner memory **71d** is a storage medium that stores information related to the toner cartridge **40d**. The toner memories **71a**, **71b**, **71c**, and **71d** are each an example of a “memory”.

The toner memories **71a**, **71b**, **71c**, and **71d** are each stored with various types of information related to a respective one of the toner cartridges **40a**, **40b**, **40c**, and **40d**. For example, the toner memories **71a**, **71b**, **71c**, and **71d** are each stored with at least one of identification information for identification of a respective one of the toner cartridges **40a**, **40b**, **40c**, and **40d**, and lifetime information indicating a lifetime of the respective one of the toner cartridges **40a**, **40b**, **40c**, and **40d**. The identification information of each of the toner cartridges **40a**, **40b**, **40c**, and **40d** includes, for

example, at least one of a manufacturing serial number of a respective one of the toner cartridges **40a**, **40b**, **40c**, and **40d**, and an identification code indicating that the respective one of the toner cartridges **40a**, **40b**, **40c**, and **40d** is a genuine product. The lifetime information of each of the toner cartridges **40a**, **40b**, **40c**, and **40d** includes, for example, at least one of a capacity for toner, a lifetime of a respective one of the developing rollers **41a**, **41b**, **41c**, and **41d**, information indicating whether a respective one of the toner cartridges **40a**, **40b**, **40c**, and **40d** is new, the cumulative number of rotations of the respective one of the developing rollers **41a**, **41b**, **41c**, and **41d**, the cumulative number of printed sheets, and an error history. Further, each of the toner memories **71a**, **71b**, **71c**, and **71d** may store compatible models or the like of a respective one of the toner cartridges **40a**, **40b**, **40c**, and **40d** in addition to the identification information and the lifetime information. The processor **51** of the main body electrical substrate **20** reads out, as the above data signal, these pieces of information from each of the toner memories **71a**, **71b**, **71c**, and **71d**, and stores these pieces of information in a main body memory mounted on the main body electrical substrate **20**. Then, the processor **51** uses these pieces of information stored in the main body memory to cause the image forming apparatus **1** to execute the printing process.

The toner substrate **70a** includes a first toner terminal **72a**, a second toner terminal **73a**, and a toner ground terminal **74a**. The toner substrate **70b** includes a first toner terminal **72b**, a second toner terminal **73b**, and a toner ground terminal **74b**. The toner substrate **70c** includes a first toner terminal **72c**, a second toner terminal **73c**, and a toner ground terminal **74c**. The toner substrate **70d** includes a first toner terminal **72d**, a second toner terminal **73d**, and a toner ground terminal **74d**.

The first toner terminals **72a**, **72b**, **72c**, and **72d** are each an example of a “first cartridge terminal”. The second toner terminals **73a**, **73b**, **73c**, and **73d** are each an example of a “second cartridge terminal”. The toner ground terminals **74a**, **74b**, **74c**, and **74d** are each an example of a “cartridge ground terminal”.

In the toner substrate **70a**, the first toner terminal **72a**, the second toner terminal **73a**, and the toner ground terminal **74a** are electrically connected to the toner memory **71a**. In the toner substrate **70b**, the first toner terminal **72b**, the second toner terminal **73b**, and the toner ground terminal **74b** are electrically connected to the toner memory **71b**. In the toner substrate **70c**, the first toner terminal **72c**, the second toner terminal **73c**, and the toner ground terminal **74c** are electrically connected to the toner memory **71c**. In the toner substrate **70d**, the first toner terminal **72d**, the second toner terminal **73d**, and the toner ground terminal **74d** are electrically connected to the toner memory **71d**.

When the drum cartridge **30a** to which the toner cartridge **40a** is attached is attached to the main body frame **10**, the first toner terminal **72a** is electrically connected to the above first main body terminal **64a**, the second toner terminal **73a** is electrically connected to the above second main body terminal **65a**, and the toner ground terminal **74a** is electrically connected to the above main body ground terminal **66a**.

When the drum cartridge **30b** to which the toner cartridge **40b** is attached is attached to the main body frame **10**, the first toner terminal **72b** is electrically connected to the above first main body terminal **64b**, the second toner terminal **73b** is electrically connected to the above second main body

terminal 65b, and the toner ground terminal 74b is electrically connected to the above main body ground terminal 66b.

When the drum cartridge 30c to which the toner cartridge 40c is attached is attached to the main body frame 10, the first toner terminal 72c is electrically connected to the above first main body terminal 64c, the second toner terminal 73c is electrically connected to the above second main body terminal 65c, and the toner ground terminal 74c is electrically connected to the above main body ground terminal 66c.

When the drum cartridge 30d to which the toner cartridge 40d is attached is attached to the main body frame 10, the first toner terminal 72d is electrically connected to the above first main body terminal 64d, the second toner terminal 73d is electrically connected to the above second main body terminal 65d, and the toner ground terminal 74d is electrically connected to the above main body ground terminal 66d.

The toner substrate 70a includes a toner pull-up resistor 75a. The toner substrate 70b includes a toner pull-up resistor 75b. The toner substrate 70c includes a toner pull-up resistor 75c. The toner substrate 70d includes a toner pull-up resistor 75d. The toner pull-up resistors 75a, 75b, 75c, and 75d are each an example of a "cartridge pull-up resistor". The toner pull-up resistors 75a, 75b, 75c, and 75d are electrical resistors.

One end of the toner pull-up resistor 75a is electrically connected to the first toner terminal 72a. One end of the toner pull-up resistor 75b is electrically connected to the first toner terminal 72b. One end of the toner pull-up resistor 75c is electrically connected to the first toner terminal 72c. One end of the toner pull-up resistor 75d is electrically connected to the first toner terminal 72d.

The other end of the toner pull-up resistor 75a is electrically connected to the second toner terminal 73a. The other end of the toner pull-up resistor 75b is electrically connected to the second toner terminal 73b. The other end of the toner pull-up resistor 75c is electrically connected to the second toner terminal 73c. The other end of the toner pull-up resistor 75d is electrically connected to the second toner terminal 73d.

<1-4. Transmission of Ground Voltage, Power Supply Voltage, Data Signal, and Synchronization Signal>

The toner memory 71a takes the ground voltage from the ground portion 53 through the toner ground terminal 74a, the main body ground terminal 66a, the relay ground terminal 63, and the main ground terminal 57. The toner memory 71b takes the ground voltage from the ground portion 53 through the toner ground terminal 74b, the main body ground terminal 66b, the relay ground terminal 63, and the main ground terminal 57. The toner memory 71c takes the ground voltage from the ground portion 53 through the toner ground terminal 74c, the main body ground terminal 66c, the relay ground terminal 63, and the main ground terminal 57. The toner memory 71d takes the ground voltage from the ground portion 53 through the toner ground terminal 74d, the main body ground terminal 66d, the relay ground terminal 63, and the main ground terminal 57.

The toner memory 71a takes the power supply voltage from the power supply unit 52 through the first toner terminal 72a, the first main body terminal 64a, the first relay terminal 61, and the first main terminal 55. The toner memory 71b takes the power supply voltage from the power supply unit 52 through the first toner terminal 72b, the first main body terminal 64b, the first relay terminal 61, and the first main terminal 55. The toner memory 71c takes the

power supply voltage from the power supply unit 52 through the first toner terminal 72c, the first main body terminal 64c, the first relay terminal 61, and the first main terminal 55. The toner memory 71d takes the power supply voltage from the power supply unit 52 through the first toner terminal 72d, the first main body terminal 64d, the first relay terminal 61, and the first main terminal 55.

The processor 51 transmits the synchronization signal and the data signal to the toner memory 71a through the second main terminal 56a, the second relay terminal 62a, the second main body terminal 65a, and the second toner terminal 73a. The processor 51 receives the data signal from the toner memory 71a through the second toner terminal 73a, the second main body terminal 65a, the second relay terminal 62a, and the second main terminal 56a.

The processor 51 transmits the synchronization signal and the data signal to the toner memory 71b through the second main terminal 56b, the second relay terminal 62b, the second main body terminal 65b, and the second toner terminal 73b. The processor 51 receives the data signal from the toner memory 71b through the second toner terminal 73b, the second main body terminal 65b, the second relay terminal 62b, and the second main terminal 56b.

The processor 51 transmits the synchronization signal and the data signal to the toner memory 71c through the second main terminal 56c, the second relay terminal 62c, the second main body terminal 65c, and the second toner terminal 73c. The processor 51 receives the data signal from the toner memory 71c through the second toner terminal 73c, the second main body terminal 65c, the second relay terminal 62c, and the second main terminal 56c.

The processor 51 transmits the synchronization signal and the data signal to the toner memory 71d through the second main terminal 56d, the second relay terminal 62d, the second main body terminal 65d, and the second toner terminal 73d. The processor 51 receives the data signal from the toner memory 71d through the second toner terminal 73d, the second main body terminal 65d, the second relay terminal 62d, and the second main terminal 56d.

The toner memories 71a, 71b, 71c, and 71d in the present embodiment each include a timer that generates a clock signal. Further, the synchronization signal in the present embodiment is a reset signal for resetting the timer of a respective one of the toner memories 71a, 71b, 71c, and 71d. Each of the toner memories 71a, 71b, 71c, and 71d generates the clock signal by resetting the timer based on the synchronization signal supplied from a respective one of the second toner terminals 73a, 73b, 73c, and 73d. Each of the toner memories 71a, 71b, 71c, and 71d takes the timing of the data signal according to the clock signal generated by a respective one of the toner memories 71a, 71b, 71c, and 71d themselves.

As described above, in the image forming apparatus 1, the power supply voltage, which is one of the power supply voltage, the data signal, and the synchronization signal, is transmitted between the main body electrical substrate 20 and the toner substrate 70a through the first main body terminal 64a and the first toner terminal 72a. The data signal and the synchronization signal, which are remaining two of the power supply voltage, the data signal, and the synchronization signal, are transmitted through the second main body terminal 65a and the second toner terminal 73a.

In the image forming apparatus 1, the power supply voltage, which is one of the power supply voltage, the data signal, and the synchronization signal, is transmitted between the main body electrical substrate 20 and the toner substrate 70b through the first main body terminal 64b and

the first toner terminal 72b. The data signal and the synchronization signal, which are remaining two of the power supply voltage, the data signal, and the synchronization signal, are transmitted through the second main body terminal 65b and the second toner terminal 73b.

In the image forming apparatus 1, the power supply voltage, which is one of the power supply voltage, the data signal, and the synchronization signal, is transmitted between the main body electrical substrate 20 and the toner substrate 70c through the first main body terminal 64c and the first toner terminal 72c. The data signal and the synchronization signal, which are remaining two of the power supply voltage, the data signal, and the synchronization signal, are transmitted through the second main body terminal 65c and the second toner terminal 73c.

In the image forming apparatus 1, the power supply voltage, which is one of the power supply voltage, the data signal, and the synchronization signal, is transmitted between the main body electrical substrate 20 and the toner substrate 70d through the first main body terminal 64d and the first toner terminal 72d. The data signal and the synchronization signal, which are remaining two of the power supply voltage, the data signal, and the synchronization signal, are transmitted through the second main body terminal 65d and the second toner terminal 73d.

Therefore, it is possible to realize, by three parallel terminals, (1) taking of the ground voltage, (2) transmitting of the power supply voltage, (3) transmitting of the data signal, and (4) transmitting of the synchronization signal between the main body electrical substrate 20 and each of the toner substrates 70a, 70b, 70c, and 70d. As a result, the number of terminals can be reduced as compared with a case where (1) to (4) are realized by four parallel terminals.

The toner substrate 70a in the present embodiment includes the toner pull-up resistor 75a. The one end of the toner pull-up resistor 75a is electrically connected to the first toner terminal 72a. The other end of the toner pull-up resistor 75a is electrically connected to the second toner terminal 73a.

Thus, the data signal and the synchronization signal transmitted through the second toner terminal 73a are each less likely to take a voltage value other than high/low. Therefore, in the toner substrate 70a, the data signal and the synchronization signal are less likely to be influenced by noise. As a result, even when a wiring between the main body electrical substrate 20 and the toner substrate 70a is long, the data signal and the synchronization signal can be stably transmitted.

Similarly, in the toner substrate 70b, due to the toner pull-up resistor 75b, the data signal and the synchronization signal are also less likely to be influenced by noise. Similarly, in the toner substrate 70c, due to the toner pull-up resistor 75c, the data signal and the synchronization signal are also less likely to be influenced by noise. Similarly, in the toner substrate 70d, due to the toner pull-up resistor 75d, the data signal and the synchronization signal are also less likely to be influenced by noise.

The main substrate 50 in the present embodiment includes the main body pull-up resistors 58a, 58b, 58c, and 58d. The one ends of the main body pull-up resistors 58a, 58b, 58c, and 58d are electrically connected to the first main body terminals 64a, 64b, 64c, and 64d through the first main terminal 55 and the first relay terminal 61. The other end of the main body pull-up resistor 58a is electrically connected to the second main body terminal 65a through the second main terminal 56a and the second relay terminal 62a. The other end of the main body pull-up resistor 58b is electrically

connected to the second main body terminal 65b through the second main terminal 56b and the second relay terminal 62b. The other end of the main body pull-up resistor 58c is electrically connected to the second main body terminal 65c through the second main terminal 56c and the second relay terminal 62c. The other end of the main body pull-up resistor 58d is electrically connected to the second main body terminal 65d through the second main terminal 56d and the second relay terminal 62d.

Thus, the data signal and the synchronization signal transmitted through each of the second main body terminals 65a, 65b, 65c, and 65d are each less likely to take a voltage value other than high/low. Therefore, in the main body electrical substrate 20, the data signal and the synchronization signal are less likely to be influenced by noise. As a result, even when the wiring between the main body electrical substrate 20 and the toner substrate 70a is long, the data signal and the synchronization signal can be stably transmitted.

Further, the main substrate 50 in the present embodiment includes the main body pull-down resistor 59. The one end of the main body pull-down resistor 59 is electrically connected to the first main body terminals 64a, 64b, 64c, and 64d through the first main terminal 55 and the first relay terminal 61. The other end of the main body pull-down resistor 59 is electrically connected to the main body ground terminals 66a, 66b, 66c, and 66d through the main ground terminal 57 and the relay ground terminal 63.

Thus, when static electricity enters the first main body terminals 64a, 64b, 64c, and 64d, the static electricity can be released to the ground portion 53 through the first relay terminal 61, the first main terminal 55, and the main body pull-down resistor 59. Therefore, it is possible to prevent the processor 51 of the main substrate 50 from erroneously operating due to the static electricity.

Further, the main substrate 50 in the present embodiment includes the switch 54. By controlling the switch 54 by the processor 51, it is possible to switch between supply and stop of the power supply voltage to each of the first main body terminals 64a, 64b, 64c, and 64d. Thus, the supply of the power supply voltage can be stopped by turning off the switch 54 when the power supply voltage is unnecessary. As a result, power consumption of the image forming apparatus 1 can be reduced.

2. Second Embodiment

Next, a second embodiment will be described. The second embodiment is different from the first embodiment in that drum cartridges each include a drum substrate. Hereinafter, differences from the first embodiment will be mainly described, and repeated descriptions will be omitted for the same portions as those in the first embodiment.

FIG. 3 is a conceptual diagram of an image forming apparatus 1 according to the second embodiment. As shown in FIG. 3, the drum cartridge 30a in the present embodiment includes a drum substrate 80a. The drum cartridge 30b includes a drum substrate 80b. The drum cartridge 30c includes a drum substrate 80c. The drum cartridge 30d includes a drum substrate 80d.

The drum substrates 80a, 80b, 80c, and 80d are each an example of the "cartridge substrate". The drum substrate 80a is located at an outer surface of the drum cartridge 30a. The drum substrate 80b is located at an outer surface of the drum cartridge 30b. The drum substrate 80c is located at an outer surface of the drum cartridge 30c. The drum substrate 80d is located at an outer surface of the drum cartridge 30d.

When the toner cartridge **40a** is attached to the drum cartridge **30a**, the drum substrate **80a** is electrically connected to the toner substrate **70a**. When the toner cartridge **40b** is attached to the drum cartridge **30b**, the drum substrate **80b** is electrically connected to the toner substrate **70b**. When the toner cartridge **40c** is attached to the drum cartridge **30c**, the drum substrate **80c** is electrically connected to the toner substrate **70c**. When the toner cartridge **40d** is attached to the drum cartridge **30d**, the drum substrate **80d** is electrically connected to the toner substrate **70d**.

When the drum cartridge **30a** to which the toner cartridge **40a** is attached is attached to the main body frame **10**, the drum substrate **80a** is electrically connected to the main body electrical substrate **20** through the toner substrate **70a**. When the drum cartridge **30b** to which the toner cartridge **40b** is attached is attached to the main body frame **10**, the drum substrate **80b** is electrically connected to the main body electrical substrate **20** through the toner substrate **70b**. When the drum cartridge **30c** to which the toner cartridge **40c** is attached is attached to the main body frame **10**, the drum substrate **80c** is electrically connected to the main body electrical substrate **20** through the toner substrate **70c**. When the drum cartridge **30d** to which the toner cartridge **40d** is attached is attached to the main body frame **10**, the drum substrate **80d** is electrically connected to the main body electrical substrate **20** through the toner substrate **70d**.

FIG. 4 is a block diagram showing electrical connection among the main body electrical substrate **20**, the four toner substrates **70a**, **70b**, **70c**, and **70d**, and the four drum substrates **80a**, **80b**, **80c**, and **80d**.

As shown in FIG. 4, the drum substrate **80a** includes a drum memory **81a**. The drum memory **81a** is a storage medium that stores information related to the drum cartridge **30a**. The drum substrate **80b** includes a drum memory **81b**. The drum memory **81b** is a storage medium that stores information related to the drum cartridge **30b**. The drum substrate **80c** includes a drum memory **81c**. The drum memory **81c** is a storage medium that stores information related to the drum cartridge **30c**. The drum substrate **80d** includes a drum memory **81d**. The drum memory **81d** is a storage medium that stores information related to the drum cartridge **30d**. The drum memories **81a**, **81b**, **81c**, and **81d** are each an example of the "memory".

The drum memories **81a**, **81b**, **81c**, and **81d** are each stored with various types of information related to a respective one of the drum cartridges **30a**, **30b**, **30c**, and **30d**. For example, the drum memories **81a**, **81b**, **81c**, and **81d** are each stored with at least one of identification information for identification of a respective one of the drum cartridges **30a**, **30b**, **30c**, and **30d**, and lifetime information indicating a lifetime of the respective one of the drum cartridges **30a**, **30b**, **30c**, and **30d**. The identification information of each of the drum cartridges **30a**, **30b**, **30c**, and **30d** includes, for example, at least one of a manufacturing serial number of a respective one of the drum cartridges **30a**, **30b**, **30c**, and **30d**, and an identification code indicating that the respective one of the drum cartridges **30a**, **30b**, **30c**, and **30d** is a genuine product. The lifetime information of each of the drum cartridges **30a**, **30b**, **30c**, and **30d** includes, for example, at least one of a lifetime of a respective one of the photosensitive drums **31a**, **31b**, **31c**, and **31d**, information indicating whether a respective one of the drum cartridges **30a**, **30b**, **30c**, and **30d** is new, the cumulative number of rotations of the respective one of the photosensitive drums **31a**, **31b**, **31c**, and **31d**, a cumulative charging time of the respective one of the photosensitive drums **31a**, **31b**, **31c**, and **31d**, the cumulative number of printed sheets, and an error history.

Further, each of the drum memories **81a**, **81b**, **81c**, and **81d** may store compatible models of a respective one of the drum cartridges **30a**, **30b**, **30c**, and **30d**, charging characteristics of a respective one of the photosensitive drums **31a**, **31b**, **31c**, and **31d**, or the like in addition to the identification information and the lifetime information. The processor **51** of the main body electrical substrate **20** reads out, as the above data signal, these pieces of information from each of the drum memories **81a**, **81b**, **81c**, and **81d**, and stores these pieces of information in the main body memory mounted on the main body electrical substrate **20**. Then, the processor **51** uses these pieces of information stored in the main body memory to cause the image forming apparatus **1** to execute a printing process.

The drum substrate **80a** includes a first drum terminal **82a**, a second drum terminal **83a**, and a drum ground terminal **84a**. The drum substrate **80b** includes a first drum terminal **82b**, a second drum terminal **83b**, and a drum ground terminal **84b**. The drum substrate **80c** includes a first drum terminal **82c**, a second drum terminal **83c**, and a drum ground terminal **84c**. The drum substrate **80d** includes a first drum terminal **82d**, a second drum terminal **83d**, and a drum ground terminal **84d**.

The first drum terminals **82a**, **82b**, **82c**, and **82d** are each an example of the "first cartridge terminal". The second drum terminals **83a**, **83b**, **83c**, and **83d** are each an example of the "second cartridge terminal". The drum ground terminals **84a**, **84b**, **84c**, and **84d** are each an example of the "cartridge ground terminal".

In the drum substrate **80a**, the first drum terminal **82a**, the second drum terminal **83a**, and the drum ground terminal **84a** are electrically connected to the drum memory **81a**. In the drum substrate **80b**, the first drum terminal **82b**, the second drum terminal **83b**, and the drum ground terminal **84b** are electrically connected to the drum memory **81b**. In the drum substrate **80c**, the first drum terminal **82c**, the second drum terminal **83c**, and the drum ground terminal **84c** are electrically connected to the drum memory **81c**. In the drum substrate **80d**, the first drum terminal **82d**, the second drum terminal **83d**, and the drum ground terminal **84d** are electrically connected to the drum memory **81d**.

The toner substrate **70a** includes a first toner relay terminal **76a**, a second toner relay terminal **77a**, and a toner relay ground terminal **78a**. The first toner relay terminal **76a** is electrically connected to the first toner terminal **72a**. The second toner relay terminal **77a** is electrically connected to the second toner terminal **73a**. The toner relay ground terminal **78a** is electrically connected to the toner ground terminal **74a**.

The toner substrate **70b** includes a first toner relay terminal **76b**, a second toner relay terminal **77b**, and a toner relay ground terminal **78b**. The first toner relay terminal **76b** is electrically connected to the first toner terminal **72b**. The second toner relay terminal **77b** is electrically connected to the second toner terminal **73b**. The toner relay ground terminal **78b** is electrically connected to the toner ground terminal **74b**.

The toner substrate **70c** includes a first toner relay terminal **76c**, a second toner relay terminal **77c**, and a toner relay ground terminal **78c**. The first toner relay terminal **76c** is electrically connected to the first toner terminal **72c**. The second toner relay terminal **77c** is electrically connected to the second toner terminal **73c**. The toner relay ground terminal **78c** is electrically connected to the toner ground terminal **74c**.

The toner substrate **70d** includes a first toner relay terminal **76d**, a second toner relay terminal **77d**, and a toner relay

ground terminal 78d. The first toner relay terminal 76d is electrically connected to the first toner terminal 72d. The second toner relay terminal 77d is electrically connected to the second toner terminal 73d. The toner relay ground terminal 78d is electrically connected to the toner ground terminal 74d.

When the toner cartridge 40a is attached to the drum cartridge 30a, the first drum terminal 82a is electrically connected to the first toner relay terminal 76a, the second drum terminal 83a is electrically connected to the second toner relay terminal 77a, and the drum ground terminal 84a is electrically connected to the toner relay ground terminal 78a.

When the toner cartridge 40b is attached to the drum cartridge 30b, the first drum terminal 82b is electrically connected to the first toner relay terminal 76b, the second drum terminal 83b is electrically connected to the second toner relay terminal 77b, and the drum ground terminal 84b is electrically connected to the toner relay ground terminal 78b.

When the toner cartridge 40c is attached to the drum cartridge 30c, the first drum terminal 82c is electrically connected to the first toner relay terminal 76c, the second drum terminal 83c is electrically connected to the second toner relay terminal 77c, and the drum ground terminal 84c is electrically connected to the toner relay ground terminal 78c.

When the toner cartridge 40d is attached to the drum cartridge 30d, the first drum terminal 82d is electrically connected to the first toner relay terminal 76d, the second drum terminal 83d is electrically connected to the second toner relay terminal 77d, and the drum ground terminal 84d is electrically connected to the toner relay ground terminal 78d.

The drum substrate 80a includes a drum pull-up resistor 85a. The drum substrate 80b includes a drum pull-up resistor 85b. The drum substrate 80c includes a drum pull-up resistor 85c. The drum substrate 80d includes a drum pull-up resistor 85d. The drum pull-up resistors 85a, 85b, 85c, and 85d are each an example of the "cartridge pull-up resistor". The drum pull-up resistors 85a, 85b, 85c, and 85d are electrical resistors.

One end of the drum pull-up resistor 85a is electrically connected to the first drum terminal 82a. The other end of the drum pull-up resistor 85a is electrically connected to the second drum terminal 83a. One end of the drum pull-up resistor 85b is electrically connected to the first drum terminal 82b. The other end of the drum pull-up resistor 85b is electrically connected to the second drum terminal 83b. One end of the drum pull-up resistor 85c is electrically connected to the first drum terminal 82c. The other end of the drum pull-up resistor 85c is electrically connected to the second drum terminal 83c. One end of the drum pull-up resistor 85d is electrically connected to the first drum terminal 82d. The other end of the drum pull-up resistor 85d is electrically connected to the second drum terminal 83d.

The drum memory 81a takes the ground voltage from the ground portion 53 through the drum ground terminal 84a, the toner relay ground terminal 78a, the toner ground terminal 74a, the main body ground terminal 66a, the relay ground terminal 63, and the main ground terminal 57. The drum memory 81b takes the ground voltage from the ground portion 53 through the drum ground terminal 84b, the toner relay ground terminal 78b, the toner ground terminal 74b, the main body ground terminal 66b, the relay ground terminal 63, and the main ground terminal 57. The drum memory 81c takes the ground voltage from the ground

portion 53 through the drum ground terminal 84c, the toner relay ground terminal 78c, the toner ground terminal 74c, the main body ground terminal 66c, the relay ground terminal 63, and the main ground terminal 57. The drum memory 81d takes the ground voltage from the ground portion 53 through the drum ground terminal 84d, the toner relay ground terminal 78d, the toner ground terminal 74d, the main body ground terminal 66d, the relay ground terminal 63, and the main ground terminal 57.

The drum memory 81a takes the power supply voltage from the power supply unit 52 through the first drum terminal 82a, the first toner relay terminal 76a, the first toner terminal 72a, the first main body terminal 64a, the first relay terminal 61, and the first main terminal 55. The drum memory 81b takes the power supply voltage from the power supply unit 52 through the first drum terminal 82b, the first toner relay terminal 76b, the first toner terminal 72b, the first main body terminal 64b, the first relay terminal 61, and the first main terminal 55. The drum memory 81c takes the power supply voltage from the power supply unit 52 through the first drum terminal 82c, the first toner relay terminal 76c, the first toner terminal 72c, the first main body terminal 64c, the first relay terminal 61, and the first main terminal 55. The drum memory 81d takes the power supply voltage from the power supply unit 52 through the first drum terminal 82d, the first toner relay terminal 76d, the first toner terminal 72d, the first main body terminal 64d, the first relay terminal 61, and the first main terminal 55.

The processor 51 transmits the synchronization signal and the data signal to the drum memory 81a through the second main terminal 56a, the second relay terminal 62a, the second main body terminal 65a, the second toner terminal 73a, the second toner relay terminal 77a, and the second drum terminal 83a. The processor 51 receives the data signal from the drum memory 81a through the second drum terminal 83a, the second toner relay terminal 77a, the second toner terminal 73a, the second main body terminal 65a, the second relay terminal 62a, and the second main terminal 56a.

The processor 51 transmits the synchronization signal and the data signal to the drum memory 81b through the second main terminal 56b, the second relay terminal 62b, the second main body terminal 65b, the second toner terminal 73b, the second toner relay terminal 77b, and the second drum terminal 83b. The processor 51 receives the data signal from the drum memory 81b through the second drum terminal 83b, the second toner relay terminal 77b, the second toner terminal 73b, the second main body terminal 65b, the second relay terminal 62b, and the second main terminal 56b.

The processor 51 transmits the synchronization signal and the data signal to the drum memory 81c through the second main terminal 56c, the second relay terminal 62c, the second main body terminal 65c, the second toner terminal 73c, the second toner relay terminal 77c, and the second drum terminal 83c. The processor 51 receives the data signal from the drum memory 81c through the second drum terminal 83c, the second toner relay terminal 77c, the second toner terminal 73c, the second main body terminal 65c, the second relay terminal 62c, and the second main terminal 56c.

The processor 51 transmits the synchronization signal and the data signal to the drum memory 81d through the second main terminal 56d, the second relay terminal 62d, the second main body terminal 65d, the second toner terminal 73d, the second toner relay terminal 77d, and the second drum terminal 83d. The processor 51 receives the data signal from the drum memory 81d through the second drum terminal 83d, the second toner relay terminal 77d, the second toner terminal 73d, the second main body terminal 65d, the second relay terminal 62d, and the second main terminal 56d.

terminal **73d**, the second main body terminal **65d**, the second relay terminal **62d**, and the second main terminal **56d**.

The drum memories **81a**, **81b**, **81c**, and **81d** in the present embodiment each include a timer that generates a clock signal. Further, the synchronization signal in the present embodiment is a reset signal for resetting the timer of a respective one of the drum memories **81a**, **81b**, **81c**, and **81d**. Each of the drum memories **81a**, **81b**, **81c**, and **81d** generates the clock signal by resetting the timer based on the synchronization signal supplied from a respective one of the second drum terminals **83a**, **83b**, **83c**, and **83d**. The drum memory **81a** takes a timing of the data signal according to the clock signal generated by the drum memory **81a** itself.

As described above, in the image forming apparatus **1**, the power supply voltage, which is one of the power supply voltage, the data signal, and the synchronization signal, is transmitted between the main body electrical substrate **20** and the drum substrate **80a** through the first main body terminal **64a**, the first toner terminal **72a**, the first toner relay terminal **76a**, and the first drum terminal **82a**. The data signal and the synchronization signal, which are remaining two of the power supply voltage, the data signal, and the synchronization signal, are transmitted through the second main body terminal **65a**, the second toner terminal **73a**, the second toner relay terminal **77a**, and the second drum terminal **83a**.

In the image forming apparatus **1**, the power supply voltage, which is one of the power supply voltage, the data signal, and the synchronization signal, is transmitted between the main body electrical substrate **20** and the drum substrate **80b** through the first main body terminal **64b**, the first toner terminal **72b**, the first toner relay terminal **76b**, and the first drum terminal **82b**. The data signal and the synchronization signal, which are remaining two of the power supply voltage, the data signal, and the synchronization signal, are transmitted through the second main body terminal **65b**, the second toner terminal **73b**, the second toner relay terminal **77b**, and the second drum terminal **83b**.

In the image forming apparatus **1**, the power supply voltage, which is one of the power supply voltage, the data signal, and the synchronization signal, is transmitted between the main body electrical substrate **20** and the drum substrate **80c** through the first main body terminal **64c**, the first toner terminal **72c**, the first toner relay terminal **76c**, and the first drum terminal **82c**. The data signal and the synchronization signal, which are remaining two of the power supply voltage, the data signal, and the synchronization signal, are transmitted through the second main body terminal **65c**, the second toner terminal **73c**, the second toner relay terminal **77c**, and the second drum terminal **83c**.

In the image forming apparatus **1**, the power supply voltage, which is one of the power supply voltage, the data signal, and the synchronization signal, is transmitted between the main body electrical substrate **20** and the drum substrate **80d** through the first main body terminal **64d**, the first toner terminal **72d**, the first toner relay terminal **76d**, and the first drum terminal **82d**. The data signal and the synchronization signal, which are remaining two of the power supply voltage, the data signal, and the synchronization signal, are transmitted through the second main body terminal **65d**, the second toner terminal **73d**, the second toner relay terminal **77d**, and the second drum terminal **83d**.

Therefore, it is possible to realize, by three parallel terminals, (1) taking of the ground voltage, (2) transmitting of the power supply voltage, (3) transmitting of the data signal, and (4) transmitting of the synchronization signal between the main body electrical substrate **20** and each of

the drum substrates **80a**, **80b**, **80c**, and **80d**. As a result, the number of terminals can be reduced as compared with the case where (1) to (4) are realized by the four parallel terminals.

5 The drum substrate **80a** in the present embodiment includes the drum pull-up resistor **85a**. The one end of the drum pull-up resistor **85a** is electrically connected to the first drum terminal **82a**. The other end of the drum pull-up resistor **85a** is electrically connected to the second drum terminal **83a**.

Thus, the data signal and the synchronization signal transmitted through the second drum terminal **83a** are each less likely to take a voltage value other than high/low. Therefore, in the drum substrate **80a**, the data signal and the synchronization signal are less likely to be influenced by noise. As a result, even when a wiring between the main body electrical substrate **20** and the drum substrate **80a** is long, the data signal and the synchronization signal can be stably transmitted.

Similarly, in the drum substrate **80b**, due to the drum pull-up resistor **85b**, the data signal and the synchronization signal are also less likely to be influenced by noise. Similarly, in the drum substrate **80c**, due to the drum pull-up resistor **85c**, the data signal and the synchronization signal are also less likely to be influenced by noise. Similarly, in the drum substrate **80d**, due to the drum pull-up resistor **85d**, the data signal and the synchronization signal are also less likely to be influenced by noise.

30 In the present embodiment, the drum substrate **80a** is electrically connected to the main body electrical substrate **20** through the toner substrate **70a**. Therefore, the number of terminals can be reduced as compared with a case where the toner substrate **70a** and the drum substrate **80a** are connected to the main body electrical substrate **20** in parallel. In the present embodiment, the drum substrate **80b** is electrically connected to the main body electrical substrate **20** through the toner substrate **70b**. Therefore, the number of terminals can be reduced as compared with a case where the toner substrate **70b** and the drum substrate **80b** are connected to the main body electrical substrate **20** in parallel. In the present embodiment, the drum substrate **80c** is electrically connected to the main body electrical substrate **20** through the toner substrate **70c**. Therefore, the number of terminals can be reduced as compared with a case where the toner substrate **70c** and the drum substrate **80c** are connected to the main body electrical substrate **20** in parallel. In the present embodiment, the drum substrate **80d** is electrically connected to the main body electrical substrate **20** through the toner substrate **70d**. Therefore, the number of terminals can be reduced as compared with a case where the toner substrate **70d** and the drum substrate **80d** are connected to the main body electrical substrate **20** in parallel.

55 3. Modifications

Although the first embodiment and the second embodiment have been described above, the present disclosure is not limited to the above embodiments.

60 <3-1. First Modification>

FIG. 5 is a block diagram showing electrical connection among the main body electrical substrate **20**, the four toner substrates **70a**, **70b**, **70c**, and **70d**, and the four drum substrates **80a**, **80b**, **80c**, and **80d** in a first modification. The first modification is different from the second embodiment in that each of the toner substrates **70a**, **70b**, **70c**, and **70d** does not include a toner pull-up resistor.

A distance between the toner substrate **70a** and the drum substrate **80a** is short. Specifically, a wiring distance between the toner substrate **70a** and the drum substrate **80a** is shorter than a wiring distance between the main body electrical substrate **20** and the toner substrate **70a**. Therefore, when the drum substrate **80a** includes the drum pull-up resistor **85a**, the first toner relay terminal **76a** of the toner substrate **70a** is connected to the first drum terminal **82a** of the drum substrate **80a**, and the second toner relay terminal **77a** of the toner substrate **70a** is connected to the second drum terminal **83a** of the drum substrate **80a**, an influence of the noise on the data signal and the synchronization signal can be reduced to some extent in the toner substrate **70a** even if the toner substrate **70a** is not provided with the toner pull-up resistor.

Similarly, in each of the other toner substrates **70b**, **70c**, and **70d**, an influence of the noise can also be reduced by a respective one of the drum pull-up resistors **85b**, **85c**, and **85d** without providing the toner pull-up resistor. As a result, it is possible to stably transmit the data signal and the synchronization signal while reducing the number of components of each of the toner substrates **70a**, **70b**, **70c**, and **70d**.

<3-2. Second Modification>

FIG. 6 is a block diagram showing electrical connection among the main body electrical substrate **20**, the four toner substrates **70a**, **70b**, **70c**, and **70d**, and the four drum substrates **80a**, **80b**, **80c**, and **80d** in a second modification. The second modification is different from the second embodiment in that each of the drum substrates **80a**, **80b**, **80c**, and **80d** does not include a drum pull-up resistor.

A distance between the toner substrate **70a** and the drum substrate **80a** is short. Specifically, a wiring distance between the toner substrate **70a** and the drum substrate **80a** is shorter than a wiring distance between the main body electrical substrate **20** and the toner substrate **70a**. Therefore, when the toner substrate **70a** includes the toner pull-up resistor **75a**, an influence of the noise on the data signal and the synchronization signal can be reduced to some extent in the drum substrate **80a** even if the drum substrate **80a** is not provided with the drum pull-up resistor.

Similarly, in each of the other drum substrates **80b**, **80c**, and **80d**, an influence of the noise on the data signal and the synchronization signal can also be reduced by a respective one of the toner pull-up resistors **75b**, **75c**, and **75d** without providing the drum pull-up resistor. As a result, it is possible to stably transmit the data signal and the synchronization signal while reducing the number of components of each of the drum substrates **80a**, **80b**, **80c**, and **80d**.

<3-3. Third Modification>

FIG. 7 is a block diagram showing electrical connection among the main body electrical substrate **20**, the four toner substrates **70a**, **70b**, **70c**, and **70d**, and the four drum substrates **80a**, **80b**, **80c**, and **80d** in a third modification. The third modification is different from the second modification in that each of the drum substrates **80a**, **80b**, **80c**, and **80d** does not include a first drum terminal.

In the third modification, the power supply voltage transmitted from the first main body terminal **64a** is not directly supplied to the drum memory **81a**. The drum memory **81a** is driven by obtaining a voltage from the data signal and the synchronization signal which are supplied from the second main body terminal **65a** through the second toner terminal **73a**, the second toner relay terminal **77a**, and the second drum terminal **83a**.

Similarly, the drum memory **81b** is driven by obtaining a voltage from the data signal and the synchronization signal

which are supplied from the second main body terminal **65b** through the second toner terminal **73b**, the second toner relay terminal **77b**, and the second drum terminal **83b**. The drum memory **81c** is driven by obtaining a voltage from the data signal and the synchronization signal which are supplied from the second main body terminal **65c** through the second toner terminal **73c**, the second toner relay terminal **77c**, and the second drum terminal **83c**. The drum memory **81d** is driven by obtaining a voltage from the data signal and the synchronization signal which are supplied from the second main body terminal **65d** through the second toner terminal **73d**, the second toner relay terminal **77d**, and the second drum terminal **83d**.

Thus, the first drum terminal can be eliminated from each of the drum substrates **80a**, **80b**, **80c**, and **80d**. Therefore, the number of terminals of each of the drum substrates **80a**, **80b**, **80c**, and **80d** can be further reduced.

Similarly, the number of terminals can also be reduced in each of the toner substrates **70a**, **70b**, **70c**, and **70d**. For example, in a configuration of the first embodiment, each of the toner memories **71a**, **71b**, **71c**, and **71d** may be driven by obtaining a voltage from the data signal and the synchronization signal which are supplied through a respective one of the second toner terminals **73a**, **73b**, **73c**, and **73d**. As a result, a first toner terminal can be eliminated from each of the toner substrates **70a**, **70b**, **70c**, and **70d**.

<3-4. Fourth Modification>

FIG. 8 is a block diagram showing electrical connection among the main body electrical substrate **20**, the four toner substrates **70a**, **70b**, **70c**, and **70d**, and the four drum substrates **80a**, **80b**, **80c**, and **80d** in a fourth modification. The fourth modification is different from the second embodiment in that the number of second main terminals **56** included in the main substrate **50** is one and that the number of second relay terminals **62** included in the relay substrate **60** is one.

In the main substrate **50** in FIG. 8, one second main terminal **56** is electrically connected to the processor **51**. In the relay substrate **60** in FIG. 8, the four second main body terminals **65a**, **65b**, **65c**, and **65d** are electrically connected to one second relay terminal **62**. The second main terminal **56** and the second relay terminal **62** are electrically connected to each other.

In the fourth modification, an address signal is included in a data signal transmitted from the processor **51** to the second main terminal **56**. The address signal is a signal for designating which memory of the four toner memories **71a**, **71b**, **71c**, and **71d**, and the four drum memories **81a**, **81b**, **81c**, and **81d** is a transmission destination. When the data signal is output from the processor **51**, only a memory designated by the address signal among the four toner memories **71a**, **71b**, **71c**, and **71d**, and the four drum memories **81a**, **81b**, **81c**, and **81d** receives the data signal.

Thus, the number of second main terminals of the main substrate **50** can be reduced. Further, the number of second relay terminals of the relay substrate **60** can also be reduced. Therefore, the number of terminals in the main body electrical substrate **20** can be further reduced.

However, in the fourth modification, different data signals cannot be simultaneously transmitted from the processor **51** to two or more memories. In contrast, in configurations of the first embodiment, the second embodiment, the first modification, the second modification, and the third modification, different data signals can be simultaneously transmitted from the processor **51** to a plurality of memories. Therefore, when a communication speed with memories is emphasized, it is preferable to adopt the configuration of the

first embodiment, the second embodiment, the first modification, the second modification, or the third modification.

<3-5. Fifth Modification>

In the above embodiments, the toner memories 71a, 71b, 71c, and 71d, and the drum memories 81a, 81b, 81c, and 81d each include the timer that generates the clock signal. The synchronization signals transmitted from the main body electrical substrate 20 to the memories 71a, 71b, 71c, 71d, 81a, 81b, 81c, and 81d are each the reset signal for resetting the timer.

However, each of the toner memories 71a, 71b, 71c, and 71d, and the drum memories 81a, 81b, 81c, and 81d may not include the timer that generates the clock signal. In this case, synchronization signals transmitted from the main body electrical substrate 20 to the memories 71a, 71b, 71c, 71d, 81a, 81b, 81c, and 81d may be clock signals.

<3-6. Sixth Modification>

In the above embodiments, first main body terminals of a main body electrical substrate are each the terminal that transmits the power supply voltage, and second main body terminals of the main body electrical substrate are each the terminal that transmits the synchronization signal and the data signal. However, each of the first main body terminals of the main body electrical substrate may be a terminal that transmits a clock signal which is a synchronization signal, and each of the second main body terminals of the main body electrical substrate may be a terminal that transmits a data signal.

In this case, each toner memory receives the clock signal through a respective one of first toner terminals and receives the data signal through a respective one of second toner terminals. At this time, each toner memory may be driven by obtaining a voltage from a respective one of these clock signals or data signals. Each drum memory receives the clock signal through a respective one of first drum terminals and receives the data signal through a respective one of second drum terminals. At this time, each drum memory may be driven by obtaining a voltage from a respective one of these clock signals or data signals.

That is, the first main body terminal of the main body electrical substrate may substantially transmit the power supply voltage and the clock signal. The second main body terminal of the main body electrical substrate may substantially transmit the power supply voltage and the data signal.

<3-7. Seventh Modification>

FIG. 9 is a block diagram showing electrical connection between the main body electrical substrate 20 and each of the four toner substrates 70a, 70b, 70c, and 70d in a seventh modification. The seventh modification is different from the first embodiment in that each of the toner substrates 70a, 70b, 70c, and 70d does not include the toner pull-up resistor.

The second main body terminal 65a of the main body electrical substrate 20 is electrically connected to the second toner terminal 73a of the toner substrate 70a. Therefore, when the main body electrical substrate 20 is provided with the main body pull-up resistor 58a, an influence of the noise on the data signal and the synchronization signal transmitted between the main body electrical substrate 20 and the toner substrate 70a can be reduced to some extent even if the toner substrate 70a is not provided with the toner pull-up resistor. Similarly, the second main body terminal 65b of the main body electrical substrate 20 is electrically connected to the second toner terminal 73b of the toner substrate 70b. Therefore, when the main body electrical substrate 20 is provided with the main body pull-up resistor 58b, an influence of the noise on the data signal and the synchronization signal transmitted between the main body electrical substrate 20

and the toner substrate 70b can be reduced to some extent even if the toner substrate 70b is not provided with the toner pull-up resistor.

The second main body terminal 65c of the main body electrical substrate 20 is electrically connected to the second toner terminal 73c of the toner substrate 70c. Therefore, when the main body electrical substrate 20 is provided with the main body pull-up resistor 58c, an influence of the noise on the data signal and the synchronization signal transmitted between the main body electrical substrate 20 and the toner substrate 70c can be reduced to some extent even if the toner substrate 70c is not provided with the toner pull-up resistor. Similarly, the second main body terminal 65d of the main body electrical substrate 20 is electrically connected to the second toner terminal 73d of the toner substrate 70d. Therefore, when the main body electrical substrate 20 is provided with the main body pull-up resistor 58d, an influence of the noise on the data signal and the synchronization signal transmitted between the main body electrical substrate 20 and the toner substrate 70d can be reduced to some extent even if the toner substrate 70d is not provided with the toner pull-up resistor.

<3-8. Eighth Modification>

FIG. 10 is a block diagram showing electrical connection between the main body electrical substrate 20 and each of the four toner substrates 70a, 70b, 70c, and 70d in an eighth modification. The eighth modification is different from the first embodiment in that the main body electrical substrate 20 does not include a main body pull-up resistor.

The second main body terminal 65a of the main body electrical substrate 20 is electrically connected to the second toner terminal 73a of the toner substrate 70a. Therefore, when the toner substrate 70a is provided with the toner pull-up resistor 75a, an influence of the noise on the data signal and the synchronization signal transmitted between the main body electrical substrate 20 and the toner substrate 70a can be reduced to some extent even if the main body electrical substrate 20 is not provided with the main body pull-up resistor. Similarly, the second main body terminal 65b of the main body electrical substrate 20 is electrically connected to the second toner terminal 73b of the toner substrate 70b. Therefore, when the toner substrate 70b is provided with the toner pull-up resistor 75b, an influence of the noise on the data signal and the synchronization signal transmitted between the main body electrical substrate 20 and the toner substrate 70b can be reduced to some extent even if the main body electrical substrate 20 is not provided with the main body pull-up resistor.

The second main body terminal 65c of the main body electrical substrate 20 is electrically connected to the second toner terminal 73c of the toner substrate 70c. Therefore, when the toner substrate 70c is provided with the toner pull-up resistor 75c, an influence of the noise on the data signal and the synchronization signal transmitted between the main body electrical substrate 20 and the toner substrate 70c can be reduced to some extent even if the main body electrical substrate 20 is not provided with the main body pull-up resistor. Similarly, the second main body terminal 65d of the main body electrical substrate 20 is electrically connected to the second toner terminal 73d of the toner substrate 70d. Therefore, when the toner substrate 70d is provided with the toner pull-up resistor 75d, an influence of the noise on the data signal and the synchronization signal transmitted between the main body electrical substrate 20 and the toner substrate 70d can be reduced to some extent even if the main body electrical substrate 20 is not provided with the main body pull-up resistor.

<3-9. Other Modifications>

In the above embodiments, four drum cartridges and four toner cartridges can be attached to an image forming apparatus. However, the number of drum cartridges and the number of toner cartridges that can be attached to the image forming apparatus each may be one, two, or three, or may be five or more.

In the above embodiments, one toner cartridge is attached to one drum cartridge. However, a plurality of toner cartridges may be attached to one drum cartridge.

Further, in the above embodiments, the toner cartridge includes a developing roller. However, the toner cartridge may not include the developing roller, and the drum cartridge may include the developing roller.

In the above embodiments, the toner cartridges and the drum cartridges are shown as examples of the "cartridge". However, the "cartridge" may be an ink cartridge or a tape cassette that can be attached to the image forming apparatus.

Structures and circuit configurations in the above embodiments and modifications are merely examples. Various elements described in the above embodiments may be replaced with other known elements within a range not departing from the spirit of the present disclosure. In addition, the various elements described in the above embodiments may be appropriately combined unless any contradiction arises.

What is claimed is:

1. An image forming apparatus to which a cartridge that includes a cartridge substrate including a memory is attachable, the image forming apparatus comprising:

a main body electrical substrate;

a main body ground terminal electrically connected to the main body electrical substrate, the main body ground terminal being configured to take a ground voltage;

a first main body terminal electrically connected to the main body electrical substrate, the first main body terminal being configured to transmit one of a power supply voltage higher than the ground voltage, a data signal that indicates information written into the memory or read out from the memory, and a synchronization signal taking a timing of the data signal;

a second main body terminal electrically connected to the main body electrical substrate, the second main body terminal being configured to transmit remaining two of the power supply voltage, the data signal, and the synchronization signal; and

a main body frame to which the cartridge is attachable, wherein

the cartridge substrate includes:

a cartridge ground terminal electrically connected to the main body ground terminal in a state where the cartridge is attached to the main body frame;

a first cartridge terminal electrically connected to the first main body terminal in the state; and

a second cartridge terminal electrically connected to the second main body terminal in the state,

wherein the memory includes a timer configured to generate a clock signal, and

wherein the synchronization signal is a reset signal for resetting the timer.

2. The image forming apparatus according to claim 1, wherein

the synchronization signal is a clock signal.

3. The image forming apparatus according to claim 1, wherein

the first main body terminal is configured to transmit the power supply voltage, and

the second main body terminal is configured to transmit the data signal and the synchronization signal.

4. The image forming apparatus according to claim 1, wherein

the cartridge substrate further includes:

a cartridge pull-up resistor including one end connected to the first cartridge terminal and the other end connected to the second cartridge terminal.

5. The image forming apparatus according to claim 1, wherein

the main body electrical substrate includes:

a main body pull-up resistor including one end connected to the first main body terminal and the other end connected to the second main body terminal.

6. The image forming apparatus according to claim 1, wherein

the main body electrical substrate includes:

a switch configured to switch between supply and stop of the power supply voltage to the first main body terminal; and

a processor configured to control the switch.

7. The image forming apparatus according to claim 1, wherein

the main body electrical substrate further includes:

a main body pull-down resistor that includes one end connected to the first main body terminal and the other end connected to the main body ground terminal.

8. The image forming apparatus according to claim 1, wherein

the memory is configured to be driven by obtaining a voltage from a signal supplied from the second cartridge terminal.

9. The image forming apparatus according to claim 1, wherein

the cartridge includes:

a toner cartridge including a toner substrate being the cartridge substrate; and

a drum cartridge including a photosensitive drum, the drum cartridge including a drum substrate, wherein the drum substrate is electrically connected to the main body electrical substrate through the toner substrate.

10. The image forming apparatus according to claim 9, wherein

the toner cartridge includes a developing roller.

11. The image forming apparatus according to claim 1, wherein

the main body electrical substrate includes:

a main substrate including a processor; and

a relay substrate configured to relay connection

between the main substrate and the cartridge substrate.

12. The image forming apparatus according to claim 1, wherein

the memory is configured to store the information used by the image forming apparatus.

13. The image forming apparatus according to claim 1, wherein

the information includes at least one of identification information and lifetime information of the cartridge, and

the main body electrical substrate is configured to read out the information as the data signal from the memory, and to store the information in a main body memory mounted on the main body electrical substrate.

25

14. An image forming apparatus to which a cartridge that includes a cartridge substrate including a memory is attachable, the image forming apparatus comprising:

- a main body electrical substrate;
  - a main body ground terminal electrically connected to the main body electrical substrate, the main body ground terminal being configured to take a ground voltage;
  - a first main body terminal electrically connected to the main body electrical substrate, the first main body terminal being configured to transmit one of a power supply voltage higher than the ground voltage, a data signal that indicates information written into the memory or read out from the memory, and a synchronization signal taking a timing of the data signal;
  - a second main body terminal electrically connected to the main body electrical substrate, the second main body terminal being configured to transmit remaining two of the power supply voltage, the data signal, and the synchronization signal; and
  - a main body frame to which the cartridge is attachable, wherein the cartridge substrate includes:
    - a cartridge ground terminal electrically connected to the main body ground terminal in a state where the cartridge is attached to the main body frame;
    - a first cartridge terminal electrically connected to the first main body terminal in the state; and
    - a second cartridge terminal electrically connected to the second main body terminal in the state,
- wherein the first main body terminal is configured to transmit a clock signal being the synchronization signal, and
- wherein the second main body terminal is configured to transmit the data signal.

5

10

15

20

25

30

35

26

15. The image forming apparatus according to claim 14, wherein

the memory is configured to be driven by obtaining a voltage from a signal supplied from the first cartridge terminal or the second cartridge terminal.

16. The image forming apparatus according to claim 14, wherein

the cartridge includes:

a toner cartridge including a toner substrate being the cartridge substrate; and

a drum cartridge including a photosensitive drum, the drum cartridge including a drum substrate, wherein the drum substrate is electrically connected to the main body electrical substrate through the toner substrate.

17. The image forming apparatus according to claim 16, wherein

the toner cartridge includes a developing roller.

18. The image forming apparatus according to claims 14, wherein

the main body electrical substrate includes:

a main substrate including a processor; and

a relay substrate configured to relay connection between the main substrate and the cartridge substrate.

19. The image forming apparatus according to claim 14, wherein

the memory is configured to store the information used by the image forming apparatus.

20. The image forming apparatus according to claim 14, wherein

the information includes at least one of identification information and lifetime information of the cartridge, and

the main body electrical substrate is configured to read out the information as the data signal from the memory, and to store the information in a main body memory mounted on the main body electrical substrate.
